SPARK PLUG TEMPERATURE CONTROL

Paul G. Andres, Indianapolis, Ind., assignor to
 Bowes "Seal-Fast" Corporation, Indianapolis,
 Ind.

Application August 18, 1939, Serial No. 290,866

10 Claims. (Cl. 123—169)

This invention relates to spark plugs such as are employed upon internal combustion engines and relates particularly to means for controlling temperatures of the central insulator when used in engines of different plug heat requirements.

An important object of the invention is to provide not only an efficient heat control of the insulator but to do so without having to employ more than two packing gaskets, both being located up above the usual threaded end of the plug where large diameter shoulders may be had in order to provide the necessary cushion seal.

A still further important object of the invention is to provide an insulating contacting member that may be varied in length along the shank of the insulator in accordance with the heat requirements, the contacting member being shortened where the nose of the insulating member is to operate at a relatively high temperature and lengthened where the temperature of the nose is to be reduced. This contacting member is made out of a high heat conducting metal and is intended to operate to transfer heat laterally or radially from the shank of the insulator to this encircling conducting member and then permit the heat to be conducted along that conducting member to the outer metal shell which supports the insulating member. The entire idea is to regulate the temperature of the lower end of the shank of the insulator which is exposed, principally across its nose, to the heat of combustion within the cylinder of the engine.

A still further important object of the invention is to provide an automatic heat control means whereby the temperature of the lower end of the insulating member is automatically changed in accordance with the heat generated within the engine cylinder, the temperature of the insulating member being reduced as the heat in the cylinder increases.

It is well known that spark plugs must be designed to meet different heat conditions. For example, a spark plug having an insulator operating at a relatively cool temperature due to dissipation of heat from the insulator will foul by collecting oil when the engine temperature is relatively low, a condition encountered in warming up the average automobile engine or when a car is driven at slow speeds as in city driving. Another condition may arise where the insulator does not dissipate heat sufficiently fast to prevent its becoming damaged by overheating under excessive cylinder combustion temperatures, such as when a car is driven at high speeds on a highway, and in racing cars, or even in heavy duty

trucks. There are intermediate conditions also that must be taken care of in order to get the best performance of the spark plug.

These and other objects and advantages of the invention will become apparent to those versed in the art in the following description of the invention as illustrated in the accompanying drawing, in which

Fig. 1 is a top plan view of a plug of conventional type to which the invention is applied; 10

Fig. 2, a central longitudinal section through the plug;

Fig. 3, a side elevation in partial, longitudinal, central section of a plug having a modified form of insulator; 15

Fig. 4, a similar view illustrating a modified form of insulator heat control member;

Fig. 5, a side elevation of a plug in partial, longitudinal section showing a still further modified form; and 20

Fig. 6, a view in perspective of a skirted gasket as employed in Fig. 3.

Like characters of reference indicate like parts throughout the several views in the drawing.

Referring first to that form as illustrated in Fig. 2, the conventional metallic shell 10 is employed and formed to have a shoulder 11 below which is a threaded portion 12 formed to engage within the threaded bore of the cylinder and to carry the shoulder 11 down against a sealing gasket (not shown) in order to form a gas-tight fit with the cylinder head, all in the usual and well known manner. The shell 10 is provided with the usual inturned annular shoulder 13 to carry a gasket 14 thereon. A ceramic insulator 15 is formed in the conventional manner to have a shank 17 extending centrally through the gasket 14 downwardly into the bore provided through the threaded end portion 12.

The upper part of the insulator 15 carries an upper shoulder 18 therearound against which a sealing gasket 19 is pressed by means of the screw-threaded ferrule 20 screw-threadedly engaging internally of the upper end of the shell 10 whereby a centrally enlarged portion of the insulator 15 is compressively gripped between the shell shoulder 13 and the ferrule 20 by means of the intervening gaskets 14 and 19 respectively. It is to be noted that both of the gaskets 14 and 19 are well spaced above the threaded portion 12 and hence are in a cooler part of the shell. The two gaskets 14 and 19 are, of course, employed for the usual purpose of cushioning and sealing the insulator 15 within the shell 10 to prevent escape of gases outwardly through the shell past 55

the insulator. The gasket 14 is formed in any suitable manner, the nature of which per se does not enter into the invention.

From the gasket 14 is carried a metal skirt 21, here shown as being conical in shape to be in close proximity and preferably in immediate contact with the conical shank 11 of the insulator 15. It is to be noted that the lower end of this skirt 17 is shown in Fig. 2 as being carried down 10 into the bore within the threaded portion 12 of the shell. That is to say, the lower end of the skirt 21 is brought down in close proximity to the nose 22 of the insulator 15, this nose, of course, being normally the hottest portion of the 15 insulator.

When the plug is in use, the nose 22 becomes heated. The insulator 15, being made out of a ceramic material, is inherently a very poor heat conductor and, therefore, the insulator normally 20 has quite a range of temperatures between its extreme upper and outer end and the nose 22. This means that considerable strain is set up in the insulator itself. By placing the gaskets 14 and 19 in the upper portion of the shell 10 or at 25 least in that portion above the shoulder 11 and spacing the gaskets to be relatively close one to the other axially along the insulator 15, permits that insulator to be gripped between zones having substantially the same temperatures or at 30 least with but slight temperature difference. This alone permits the obtaining of a good seal.

Furthermore by use of the skirt 21, heat is transferred laterally from the extremely heated nose 22 into this metal skirt. Being a good conductor, heat will be carried along the skirt up 35 to the gasket 14 which is in intimate contact with the shell 10. Through this intimate contact, the heat carried up the skirt 21 is rapidly conducted to the shell 10 and thus dissipated 40 into that body where the heat may be radiated into the atmosphere from the upper portion of the shell and also conducted through the threaded portion into the water-cooled cylinder head, it being understood, of course, that the shell 10 45 itself constitutes a relatively considerable mass of metal that is heat conducting.

The skirt 21, if made of copper, may have its lower end oxidized when subjected to the heat of combustion in the cylinder. This fact is of 50 considerable advantage in that the copper oxide is normally a poor heat conductor and, therefore, heat of combustion would not be transmitted to any great extent directly up the skirt 21 by reason of the presence of this lower oxide 55 end. This would limit largely the function of the skirt 21 to the conducting of heat laterally initially from the shank 17 and then upwardly to the shell 10.

It is obvious from the foregoing description 60 of the skirt 21, that the rate of heat conduction from the shank 17 may be varied by changing the axial length of the skirt 21. That is, if the skirt is made longer, the nose 22 will be maintained at a lower temperature whereas if the 65 skirt 21 is made shorter, the nose 22 will be permitted to assume a higher temperature. The exact position of the termination of the nose 22 within the threaded portion 12 may vary and is not to be considered as being limited by the 70 positions indicated in the accompanying drawing.

Referring now to that form of the invention as shown in Fig. 3, the insulator 15 is shown as having a cylindrically formed shank 23 in place of the conical shank 17 shown in Fig. 2. In this

form, the gasket 14 will have a cylindrically extending skirt 24 brought into close contact with the shank 23. While in both Figs. 2 and 3, a slight clearance is indicated as being between the skirt and the shell 10, this clearance is extremely small and is provided merely to permit expansion of the shank of the insulator without limitation thereof as might cause fracturing of that ceramic material. Normally this clearance will substantially disappear when the plugs are 10 in use so that to all intents and purposes, there will be conduction of heat radially not only from the insulator shank to the surrounding metallic skirt but also directly from the skirt into the shell without all of the heat having to be transmitted upwardly to the gasket 14 and with little or no air gap between the skirt and the shell.

Referring now to Fig. 4, the same type insulator 15 with the cylindrical shank 23 is indicated. In this form, however, the skirt extending from the gasket 14 is shown as comprising a plurality of individual bands 25, here shown as three in number, although this number may be varied in accordance with the length of the shank 23 and also in accordance with the temperature desired to be maintained at the nose 22. In any event, these bands 25 are employed as a simple means of obtaining the desired skirt length. Where a short length is required, the bands may be omitted entirely or simply one or two bands employed. Where the length is to be increased, more bands are used. The bands are placed around the shank 23 in compressive engagement therewith and pressed into abutment one band with another so as to obtain the continuity of heat conduction required.

In Fig. 5 there is indicated a further modified form of structure in that the skirt is divided into a plurality of individual tongues 26, each having 40 its upper end engaged with the annular gasket 14. These tongues 26 may be made out of any suitable heat conducting metal. However, where an automatically controlled temperature range within the shank 23 of the insulator 15 is desired, each of these tongues 26 is preferably made 45 of bimetal wherein initial contact of each tongue 26 is had with the upper end of the shank 23 adjacent the shoulder 16 of the insulator. This permits rapid heating of the shank upon starting of the engine in which the plug is used. As 50 the temperature of the engine increases, the tongues 26 will curl or bend toward the shank 23 to increase the area of contact therewith. Thus it is to be seen that as the temperature 55 of the shank 23 increases, there will be an increasing area of contact of the tongues 26 with that shank until the maximum area of the tongues is reached to obtain the maximum heat conduction from the shank. It is, of course, 60 understood, that the tongues 26 are so positioned relative to the shank 23 and in reference to the metals employed that the desired bending of the individual tongues 26 is secured. In other words, the form as shown in Fig. 5 gives an automatic 65 thermostat control of the rate of transfer of heat from the insulator to the shell.

In further reference to the bimetal tongues 26 shown in Fig. 5, these tongues may be so positioned relative to their direction of bending 70 under application of heat that the lower free ends may be maintained in contact with the wall of the bore through the shell 10 and to operate under a buckling action to force areas above the lower ends into increasing contact with the 75

shank 23 as the temperature at the nose 22 tends to increase.

While I have herein shown and described my invention in the several forms as now best known to me, it is obvious that structure variations may be employed, particularly in the shapes of the shanks of the insulator, the particular construction of the insulator gaskets, materials employed in the heat conducting skirts, and the like, all without departing from the spirit of the invention and I, therefore, do not desire to be limited to those specific forms beyond the limitations as may be required by the following claims.

I claim:

- 15 1. In a spark plug having a metallic shell, an insulator sealed in a bore of the shell by a lower gasket, and an insulator shank extending below the gasket in spaced relation from the wall of said bore, a heat-conducting skirt extending from contact with said shell at said gasket about said shank within the space between the shank and the wall of said bore, said skirt serving to conduct heat from said shank to said shell, said skirt being formed of a plurality of bimetal members arranged to bend under temperature changes toward and away from said shank whereby the contact length of skirt with the shank will automatically vary to increase with increase in temperature.
- 20 2. In a spark plug having a metallic shell with a bore therethrough, an insulator sealed in said bore by means of a heat conducting gasket and having a shank extending from the gasket a distance therebeyond freely along said bore, and a heat conducting skirt extending from said gasket a distance along and around said shank, and relatively poor heat-conducting means on the lower end of said skirt substantially limiting heat transfer thereto to lateral flow from said shank to the skirt.
- 25 3. In a spark plug having a metallic shell with a bore therethrough, an insulator sealed in said bore by means of a heat conducting gasket and having a shank extending on through the gasket a distance therebeyond freely along said bore, and a heat conducting skirt integrally extending from said gasket a distance along and around said shank, a part of said skirt at least consisting of metallic bands successively contacting one
- 30 40 4. In a spark plug having a metallic shell and an insulator carried in a bore of the shell, means for securing a complete, gas tight seal about an intermediate part of the insulator within an upper relatively cool zone of the shell, and heat transfer means about the insulator below said seal for conducting heat to said shell, said heat transfer means consisting of a metallic member conforming to the shape of and closely fitting along an initial upper length of said shank and having a portion in direct contact with the shell,
- 35 5. In a spark plug having a metallic shell and an insulator carried in a bore of the shell, means for securing a complete, gas tight seal about an intermediate part of the insulator within an upper relatively cool zone of the shell, and heat transfer means about the insulator below said seal for conducting heat to said shell, said heat transfer means consisting of a metallic member conforming to the shape of and closely fitting along said shank and having a portion in direct contact with the shell, and means automatically varying the shank contacting length of the metallic member in accordance with the rate of heat transfer required.
- 40 6. In a spark plug having a metallic shell with a lower threaded end portion, an external cylinder seal gasket shoulder about the shell at the upper end of said threaded portion, a bore through the shell, and a shoulder in the bore above said threaded portion, the combination with an insulator in the shell bore having an intermediate enlarged portion above said bore shoulder and a shank portion extending past the bore shoulder freely into said threaded portion, of a sealing gasket interposed between said bore shoulder and said insulator enlarged portion forming a lowermost gas seal along the insulator with said shell, and a skirt extending from the gasket along said shank for selective heat transfer therefrom to the shell in accordance with the relative lengths of the skirt and the shank, said skirt consisting of a plurality of bimetal portions arranged to go into and out of contact with the shank upon predetermined temperature fluctuations.
- 45 7. For a spark plug, an insulator sealing gasket comprising a seat annulus and an annular fin-like metallic skirt extending axially therefrom.
- 50 8. For a spark plug, an insulator sealing gasket comprising a seat annulus and an annular fin-like metallic skirt extending axially therefrom having a variable effective diameter in accordance with heat changes.
- 55 9. For a spark plug having an insulator, a gasket receiving shoulder therearound and a shank extending from said shoulder, a collar surrounding the shank having an internal diameter permitting the collar to be placed in juxtaposition with said shoulder, and a slotted metallic skirt extending from said collar about said shank.
- 60 10. For a spark plug having an insulator, a gasket receiving shoulder therearound and a shank extending from said shoulder, a collar surrounding the shank having an internal diameter permitting the collar to be placed in juxtaposition with said shoulder, and a slotted skirt extending from said collar about said shank, said skirt being formed of bimetal deforming subject to temperature changes.

PAUL G. ANDRES.
